Primary Examiner — Jack Reickel*Assistant Examiner* — Russell Carnell Smith, Jr.(57) **CLAIM**

The ornamental design for an earbud, substantially as shown and described.

DESCRIPTION

FIG. 1 is a perspective view of an earbud as seen from the front, top, and left side;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines illustrate portions of the earbud and form no part of the claimed design.
